UNITED STATES PATENT OFFICE.

THOMAS E. WARREN, OF TICONDEROGA, NEW YORK.

DOCTOR FOR CALENDERING-MACHINES.

1,144,802.

Specification of Letters Patent. Patented June 29, 1915.

Application filed April 21, 1913. Serial No. 762,540.

To all whom it may concern:

Be it known that I, THOMAS E. WARREN, a citizen of the United States, and a resident of Ticonderoga, in the county of Essex and State of New York, have invented a new and Improved Doctor for Calendering-Machines, of which the following is a full, clear, and exact description.

The invention relates to paper-making machinery, and more particularly to calenders of the stack roll type.

The object of the invention is to provide an improved form of doctor mechanism for use in a calendering machine with which a more perfect doctoring effect is produced though the pressure of the doctors on the corresponding rolls is relatively light and with which greater convenience in operation is secured.

One of the features of the invention resides in the provision of means whereby all of a plurality of doctors may be moved simultaneously into or out of operative position, or to adjust the pressure thereof on the coacting rolls, and whereby any one of the doctors may be adjusted individually to regulate its pressure on the coacting roll independently of the others. To this end a single operating mechanism is provided for moving all of the doctors together, and the individual connections from this mechanism to the several doctors are each constructed to permit of individual adjustment. These individual connections also have yielding devices combined therewith through which the movements of the operating mechanism are transmitted to the doctors. As a result of this construction, all of the doctors may be moved to the working position or to an inoperative position together, and when in the working position their pressure on the rolls may be increased or diminished together and the several doctors may be individually adjusted so that the pressure thereof may be equalized.

The invention also involves the use of a doctor blade in the form of a thin flexible strip of metal by which a yielding and elastic contact with the coacting roll is produced, whereby the doctoring effect is made more perfect with relatively light pressure of the doctor on the roll. Also, if the rolls expand unevenly due to heating, such a flexible doctor will conform more readily to the face of the roll with little if any added pressure over the heated or expanded area. Another

advantage resulting from the use of such a flexible doctor blade mounted on a metallic bar extending parallel and adjacent to the corresponding roll is that it permits of arranging the operating mechanism for the several doctors at one side only of the machine, the torsion of the supporting bars for the doctors serving to hold the latter in proper contact with the rolls. Furthermore, such thin metallic doctor blades are inexpensive, may be readily removed when worn, are more easily fitted to the corresponding rolls and are highly efficient in the performance of their functions.

The features of the invention will be better understood by reference to the following description in connection with the accompanying drawings, which show the preferred embodiment of the invention.

Figure 1 is a sectional side elevation of the doctors in contacting position with the stack of rolls of a calendering machine; Fig. 2 is a front elevation of the same, parts being in section; Fig. 3 is a front elevation of one of the doctors; Fig. 4 is an enlarged sectional side elevation of the same; Fig. 5 is an enlarged sectional plan view of one of the coupling rods and its connection with the manually-controlled rocking shaft; Fig. 6 is a sectional front elevation of the same; Fig. 7 is an enlarged sectional side elevation of one of the doctors in contact with a roll and showing a yielding connection with the coupling rod; Fig. 8 is a front elevation of the same; and Fig. 9 is a sectional side elevation of a doctor having another form of yielding connection with the coupling rod.

The calendering machine is mounted on a suitably constructed frame A, and is provided with the usual top and bottom rolls B, B' and the intermediate rolls B², the endless web of paper C passing over the top roll B and then between the successive rolls, to finally leave the machine after its passage between the bottom roll B' and the next roll B² above, as plainly indicated in Fig. 1. On the opposite sides of the series of rolls B, B² are arranged sets of doctors D, the doctors of each set engaging alternate rolls to provide a doctor for each roll, B, B², and the doctors are provided at their ends with trunnions E journaled in brackets F adjustably secured in vertical guideways G fixed on the main frame A. Each of the brackets F is preferably made in two parts F', F'', of which the member F' is adjustably

secured by bolts F^3 to the member F^2 and carries the trunnions E , and the other member F^2 is adjustably secured by bolts F^4 to the guideway G (see Figs. 7 and 8). One of the trunnions E of each doctor is provided with an outwardly-extending arm H having a slotted portion H' engaged by a pin I secured to a vertically-disposed coupling rod J mounted to slide up and down in suitable bearings J' and J^2 , of which the bearings J' are attached to the main frame A and the bearings J^2 are secured to the guideway G .

The two coupling rods J on opposite sides of the doctors D , are pivotally connected near their lower ends by pins I' with the slotted ends of crank arms K' (see Figs. 5 and 6) arranged on a rock shaft K journaled in suitable bearings K^2 attached to the main frame A . One end of the rock shaft K is provided with a suitable handle L under the control of the operator for rocking the shaft K whenever it is desired to simultaneously swing all the doctors D into or out of engagement with the peripheral faces of the stack of rolls. The handle L is adapted to be locked to a segment N so as to hold the rock shaft K in the position into which it is turned. It is understood that when the rock shaft K is unlocked and the handle L is swung to the right to rock the shaft K in the same direction then the crank arms K' swing downward, and in doing so impart a downward sliding motion to the coupling rods J so that the pins I impart a downward swinging motion to the arms H to rock the doctors D on their trunnions E and thus move the doctors into contact with the peripheral faces of the rolls. When the handle L is swung to the left the shaft K is rocked in a reverse direction so that the crank arms K' impart an upward sliding motion to the coupling arms J whereby the rods H are swung upward and the doctors D are rocked to carry them out of engagement with the rolls. Thus by the arrangement described, the operator can quickly move the several doctors into or out of peripheral engagement with the rolls.

The detail construction of each doctor D is as follows, special reference being had to Figs. 3 and 4: The doctor blade D' is made of very thin, flexible material, preferably steel or a suitable composition of bronze, and the heel portion of the blade D' is clamped between a doctor bar D^2 and a top clamping plate D^3 . This clamping plate is fastened in position on the doctor bar D^2 by bolts D^4 which are spaced a short distance away from the heel of the doctor blade D' , so that the latter can be readily adjusted on loosening the bolts D^4 to compensate for wear and to insure a proper contact of the outer projecting edge with the peripheral surface of the corresponding roll. The doctor bar D^2 is preferably in the form of

an angle iron, the top member of which supports the doctor blade D' , and the vertical member of which carries at its ends the trunnions E provided with shoulders E' on which the arms H are secured by set screws H^2 , as plainly indicated in Fig. 7.

Instead of directly connecting the arms H with the pins or pivots I attached to the coupling rods J , use is preferably made of flexible connections between the arms H and the pins or pivots I , and for this purpose the following arrangement is made, special reference being had to Figs. 7 and 8: On the free end of each arm H is pivotally mounted a block O through which extends a threaded link O' on which screw nuts O^2 and O^3 . A spring O^4 is coiled around the link O' and bears at one end on the top of the block O and at its other end against a washer O^5 resting against the nuts O^2 ; thus a yielding connection is made between the arms H and the link O' to allow of holding the doctor blade D' with more or less force in contact with the peripheral face of the corresponding roll, it being understood that the tension of the spring O^4 can be increased or diminished by screwing down or screwing up the nuts O^2 on the link O' . The nuts O^3 form adjustable stops for limiting a possible downward swinging motion of the rod H while the doctor blade D' is in contact with the corresponding roll. It will also be noticed that by the arrangement described the doctor blade D' remains in contact with its roll in the event of the roll jumping due to a wad in the web of paper passing between the corresponding rolls.

The yielding connection between the arm H and the pin I (shown in Fig. 9) is as follows: On the outer end of the arm H is pivoted a member P having an exterior screw thread P' on which screws a sleeve P^2 fulcrumed on the pin I attached to the corresponding coupling rod J . A spring P^4 is coiled on the rod P^3 within the sleeve P^2 , and the upper end of the spring abuts against a nut P^5 attached to the upper end of the rod P^3 . The lower end of the spring P^4 rests on the bottom of the sleeve P^2 . By the arrangement described, the tension of the spring P^4 can be readily adjusted by screwing the sleeve P^2 farther up or farther down on the threaded end of the member P . It will also be noticed by the arrangement described that adjustable and yielding connection is made between the arm H and the pin I to hold the doctor blade D' with the desired force in contact with the corresponding roll, and to hold the doctor blade in contact with the roll in case the latter should jump, as previously explained.

The doctor Q for the bottom roll B is provided at its ends with trunnions R journaled in brackets F^5 similar to the brackets F but secured to the main frame A (see Fig.

1). One of the trunnions R is provided with an arm S having a slotted terminal S' engaged by the pin T' of a link T slidingly engaging a block T² pivoted on a lever U fulcrumed at U' on the main frame A and having pivotal connection with a pin I' on the lower end of one of the coupling rods J. A spring T³ is coiled on the upper end of the rod T and rests with its lower end on the block T², while the upper end of the spring abuts against a nut T⁴ screwing on the upper end of the rod T. By the arrangement described a yielding connection is had between the lever U and the arm S of the doctor Q to hold the doctor with more or less force in engagement with the peripheral face of the lower roll B'. It is understood that the tension of the spring T³ can be increased or diminished by correspondingly adjusting the nut T⁴. By this construction, the upward movement of the coupling rods J will cause a downward movement of the link T so that the doctors coacting with the rollers B² will be turned angularly in one direction on their pivots and the doctor coacting with the roller B' will be turned angularly on its pivots in the opposite direction.

With the construction herein illustrated and described all of the doctors coacting with the set of calender rolls may be moved simultaneously into and out of operative position, and when in operative position they may be moved simultaneously so as to increase or decrease the pressure thereof upon the coacting rolls. A single operating mechanism effects the simultaneous movement of all of the doctors, and this operating mechanism may be mounted in any convenient position upon the frame of the machine. The operating mechanism may be provided with a lock if desired, such, for instance, as a ratchet and pawl, whereby when the doctors have been subjected to the desired degree of pressure, they may be held in the position for maintaining their pressure. It will be noted, however, that the individual connections from the several doctors to this single operating mechanism have adjusting devices therein so that any doctor may be adjusted individually. In this way, the positions of the several doctors with respect to their rolls may be individually adjusted independently of the others so that the doctors will be forced with uniform pressure against their rollers. These individual connections from the doctors to the common operating mechanism also have yieldingly devices therein, so that any doctor may move independently of the others and of the operating mechanism when such independent movement is necessary, as, for instance, when the coacting roller is moved bodily by a wad in the paper passing thereunder.

With the form of doctor blades herein shown and described, consisting of long, thin, flexible sheet metal strips, any doctor which has become worn may be readily removed and replaced, the work of fitting a new doctor in position for proper co-action with its roller may be readily accomplished, and if the roller heats and expands unevenly, the blade will shape itself to conform to the roller. Another advantage resulting from the use of doctor blades of the character herein shown mounted upon metallic supporting rods extending parallel and adjacent to the corresponding rollers, is that with this construction an operating mechanism may be employed which is located wholly at one side of the machine and which is connected to the several supports for the doctors at one end thereof only. This conduces to greater convenience in the operation of the machine and a good doctoring effect is obtained throughout the length of the rollers since the doctor blades will be held in substantially uniform contact with the rollers throughout the length of the blades by reason of the torsion of the supports for the doctor blades.

Having thus described my invention, I claim as new and desire to secure by Letters Patent:

1. In a calendering machine, the combination of a plurality of rolls, a doctor bar parallel and adjacent to each roll, a doctor mounted on each bar, trunnions at the ends of each bar, bearings for the trunnions, arms secured to the bars and an operating mechanism connected to all of said arms for simultaneously rocking the bars and the doctors thereon in said bearings to carry the doctors into and out of co-action with their corresponding rolls; substantially as described.

2. In a calendering machine, the combination of a plurality of rolls, a doctor bar parallel and adjacent to each roll, a thin, flexible metallic doctor on each doctor bar, a clamping member secured to each doctor bar to hold the doctor thereon in position, trunnions on the ends of said bars, bearings for said trunnions, an arm on one end of each of the bars, and a single operating mechanism for all of said bars connected to all of said arms for simultaneously rocking the bars in their bearings, said doctor bars serving to hold the doctors in contact with the coacting rolls with substantially equal pressure throughout the length of the doctors; substantially as described.

3. In a calendering machine, the combination of a plurality of rolls, sets of rocking doctors, one set on each side of the series of rolls, and each doctor having a blade adapted to bear at one edge on the peripheral face of the corresponding roll, arms extending from the doctors, coupling rods movable

in the direction of their lengths and connected with said arms, and manually controlled means connected with said coupling rods for simultaneously moving the doctors into and out of engagement with the corresponding rolls; substantially as described.

4. In a calendering machine, the combination of a series of rolls, sets of rocking doctors, one set on each side of the series of rolls, each doctor having a blade adapted to bear with one edge on the peripheral face of the corresponding roll, arms extending from the doctors, coupling rods, yielding and adjustable connections connecting the said arms with the said coupling rods, and a manually controlled rock shaft provided with crank arms pivotally connected with the said coupling rods.

5. In a calendering machine, the combination of a series of rolls, sets of rocking doctors, one set on each side of the series of rolls, each doctor having a blade adapted to bear with one edge on the peripheral face of the corresponding roll, arms extending from the doctors, coupling rods, and sectional connecting rods connecting the said arms with the said coupling rods, each connecting rod having pivoted members, of which one is connected with the arm and the other with the coupling rod, a sleeve screwing on one of the said members and slidably engaging the other member, and a spring interposed between the said sleeve and the said sliding member.

6. In a calendering machine, the combination of a series of rolls, sets of rocking doctors, one set on each side of the series of rolls, each doctor having a blade adapted to bear with one edge on the peripheral face of the corresponding roll, arms extending from the doctors, coupling rods, sectional connecting rods connecting the said arms with the said coupling rods, each connecting rod having pivoted members of which one is connected with the arm and the other with the coupling rod, a sleeve screwing on one of the said members and slidably engaging the other member, a spring interposed between the said sleeve and the said sliding member, a manually-controlled rock shaft provided with crank arms pivotally connected with the said coupling rods, and locking means for the said rock shaft.

7. In a calendering machine, the combination of a plurality of rolls, a doctor extending parallel and adjacent to each roll, a support for each doctor movable to carry the doctor into and out of operative position, an operating mechanism connected to all of the doctors for simultaneously moving them, and means for effecting individual adjustment of any one of the doctors; substantially as described.

8. In a calendering machine, the combination of a plurality of rolls, a doctor extend-

ing parallel and adjacent to each roll, a plurality of rocking bars, each forming a support for one of the doctors, an operating mechanism common to all of the doctor bars, and individual connections from the operating mechanism to each of the doctor bars, each of which mechanisms is individually adjustable to vary the angular position of the doctor bar connected thereto relatively to the corresponding roll; substantially as described.

9. In a calendering machine, the combination of a plurality of rolls, a doctor extending parallel and adjacent to each roll, a support for each doctor movable to carry the doctor into and out of operative position, and operating mechanism common to all of the doctors and individual adjustable yielding connections from the operating mechanism to all of said supports, each of which mechanisms is individually adjustable to vary the angular position of the support relatively to the corresponding roll; substantially as described.

10. In a calendering machine, the combination of a series of rolls, a plurality of rocking doctors, each having a blade adapted to bear at one edge on the peripheral face of the corresponding roll, an arm extending laterally from each doctor, coupling rods, yielding connections between said arms and the coupling rods, and means connected to the coupling rods for moving the latter and thereby rocking the doctors into and out of engagement with their respective rolls; substantially as described.

11. In a calendering machine, the combination of a series of rolls, sets of rocking doctors, one set on each side of the series of rolls, each doctor having a blade adapted to bear with one edge on the peripheral face of the corresponding roll, arms extending from the doctors, vertically movable coupling rods connected with the arms of the sets of doctors, a manually controlled rock shaft provided with crank arms having slotted ends, and pins pivotally connecting the slotted ends of said crank arms with the said coupling rods.

12. In a calendering machine, the combination of a series of rolls, sets of rocking doctors, one set on each side of the series of rolls, each doctor having a blade adapted to bear with one edge on the peripheral face of the corresponding roll, arms extending from the doctors, coupling rods mounted to move up and down, pins secured to said coupling rods, and yielding connections between the said arms and the said pins.

13. In a calendering machine, the combination of a series of rolls, sets of rocking doctors, one set on each side of the series of rolls, each doctor having a blade adapted to bear with one edge on the peripheral face of the corresponding roll, arms extending

from the doctors, vertically disposed coupling rods, bearings in which the said coupling rods are mounted to slide up and down, and connections between the said arms 5 and the said coupling rods.

14. In a calendering machine, a set of coacting rolls arranged in vertical alignment, a plurality of rocking doctors each coacting with one of said rolls, and a single 10 operating mechanism connected to all of said doctors for rocking them simultaneously, said mechanism being arranged to rock the doctor coacting with the roll at the end of the series in one direction and to 15 rock all of the other doctors in the opposite direction; substantially as described.

15. In a calendering machine, the combination with a calendering roll, of a thin flexible doctor blade therefor, a rocking bar 20 carrying the blade, and an operating device connected to one end only of the bar and thereby applying the doctor blade to the roll with a force due to the torsional strain set up in the bar from one end thereof.

25 16. In a calendering machine, the combination of a roll, a doctor bar of angular cross-section extending parallel and adjacent to the roll, journals in which the ends of the bar are pivotally mounted, a thin, flat, 30 flexible doctor, mounted on the bar, and an operating device connected to one end only of said bar for rocking the bar to carry the doctor into and out of coaction with the roll.

35 17. In a calendering machine, the combination of a roll, a doctor bar extending parallel and adjacent to the roll and capable of a limited amount of torsional movement, journals in which the ends of the bar are pivotally mounted, a thin, flexible doctor 40 mounted on the bar, and an operating device connected to one end only of said bar for rocking the bar to carry the doctor into and out of coaction with the roll, the torsion of the bar serving to hold the doctor in co- 45 action with the roll throughout the length of the roll.

50 18. In a calendering machine, the combination of a plurality of rolls, a doctor bar parallel and adjacent to each roll, a thin, flexible doctor mounted on each bar, journals in which the ends of each bar are mounted, an operating device on one end only of each bar, the several operating devices being upon the adjacent ends of the several bars, and a 55 single operating mechanism connected to all of said devices for simultaneously rocking all of the bars in their journals.

59 19. In a calendering machine, two parallel frames, a set of calendering rolls extending

between and journaled in said frames, a 60 doctor bar extending parallel to each roll and having its ends pivotally mounted on said frames, a thin, flexible doctor on each bar adapted to coact with the adjacent roll, a laterally-extending arm on one end of 65 each bar, all of the several arms being adjacent to the same frame member, and a single operating mechanism connected to all of said arms.

20. In a calendering machine, the combination 70 of a plurality of rolls, doctor bars pivotally mounted parallel and adjacent to the rolls, thin, flexible doctors mounted on the bars, an operating device connected to all of the bars for rocking them simultaneously, 75 and a retainer coacting with the operating device for holding that device and the doctors moved thereby in any desired position, whereby the doctors may be held out of contact with their respective rollers 80 or in contact therewith with any desired degree of pressure.

21. In a calendering machine, the combination 85 of a plurality of rolls, doctor bars pivotally mounted parallel and adjacent to the rolls, thin, flexible doctors mounted on the bars, a single operating device common to all of the bars, individual connections from said device to each bar having adjustable devices therein, and a retainer coacting with 90 the operating device for holding that device and the doctors moved thereby in any desired position, whereby the doctors may be held out of contact with their respective rollers or in contact therewith with any de- 95 sired degree of pressure.

22. In a calendering machine, the combination 100 of a plurality of rolls, doctor bars pivotally mounted parallel and adjacent to the rolls, thin, flexible doctors mounted on the bars, a single operating device common to all of the bars, individual yielding connections between the operating device and the several bars, and a retainer coacting with the operating device for holding that device 105 and the doctors moved thereby in any desired position, whereby the doctors may be held out of engagement with their respective rolls or in engagement therewith with any desired degree of pressure.

In testimony whereof I have signed my name to this specification in the presence of two subscribing witnesses.

THOMAS E. WARREN.
